BACK FOR DOCTOR BLADES

William P. Dapses, Salem, Oreg., assignor to Lodding Engineering Corporation, Auburn, Mass., a corporation of Massachusetts

Filed Dec. 14, 1962, Ser. No. 244,634
7 Claims. (Cl. 15—256.51)

This invention relates to a new and improved doctor back construction and particularly to a simplified construction, together with means for damping vibrations in the doctor blade when it is used in its ordinary function of scraping roll surfaces and the like.

The present construction involves a relatively simple elongated hollow tubular member on or in which is mounted an elongated flat rectangular plate, this plate having an edge extending exteriorly of the elongated tubular member and having mounted thereon a blade holder and a blade, said tubular member being mounted more or less in the usual manner by journals at the ends thereof and being filled with a pourable, discrete material such as sand which acts as a damping agent for the doctor blade which would otherwise tend to vibrate.

Further objects of the invention also include the application of heavier weight to the sand or similar material which is used to fill the tubular member and this can take the form of a discrete metal for instance lead shot or the like which is dispersed throughout the sand and which lends further weight to the construction at a relatively small cost in order to provide a simple inexpensive doctor back which, however, is provided with the combination of sand and lead shot to provide against unwanted vibration.

The invention further relates to arrangements and combinations of parts which will be hereinafter described and more particularly set forth in the appended claims.

Reference is to be had to the accompanying drawings, in which

FIG. 1 is a view in elevation with parts cut away illustrating the invention;

FIG. 2 is a section on line 2—2 of FIG. 1, and

FIG. 3 is an end view, looking in the direction of arrow 3 in FIG. 1.

Referring to the drawings in detail, the reference numeral 10 indicates a roll surface being doctored. This roll is mounted in any way desired and extends across the machine frame in the usual way. On the machine frame at opposite sides thereof there are mounted brackets 12 upon which are mounted doctor journal bearings 14 swivelly mounting doctor journals 16, these being aligned and capable of being oscillated by means of for instance a hydraulic or pneumatic cylinder 18 in order to apply greater or less pressure of the doctor blade to the surface being doctored as is well known in the art. The hydraulic or pneumatic cylinder 18 is mounted in any way desired on the machine frame as for instance upon structural brackets 20 which may be in turn hung or suspended from brackets 12 and the cylinder has a pivot connection 22 with an arm 24 mounted at 26 fast to the journal 16 in the usual manner.

The two journals 16 pivotally mount between them an elongated hollow tubular member generally indicated by the reference numeral 28. This member is preferably made of aluminum or other light weight material for reducing the overall weight and cost of the usual doctor blade construction. However, the tubular member 28 may be of any cross sectional form. It is here shown as cylindrical and of course it extends from end-to-end of the roll 10.

Diametrically mounted the entire length of tubing 28 there is a plate indicated at 30, this plate being elongated, flat and having parallel edges. It extends completely across the tubular member 28 essentially dividing the lat-

2

ter into two halves and as a matter of fact the tubular member 28 may be fabricated in this manner. In any event, the plate 30 extends at 32 outwardly diametrically of tubular member 28 and carries at its forward edge a conventional blade holder 34 in turn carrying a conventional blade 36.

The ends of the tubular member 28 are closed by end plates as indicated at 38 and any conventional means such as bolts or the clips shown at 40 can be used to secure the parts together. The tubular member 28 is substantially filled with a heavy, pourable, discrete vibration damping material such as for instance sand. As much or as little sand may be contained within tubular member 28 as is found desirable in order to dampen the vibration to the degree necessary. The sand is easily poured into the tubular member upon removal of one of the end plates 38. The sand adds weight to the construction to provide the damping effect desired.

In the event that additional damping is found to be required, then heavier material can be dispersed throughout the sand as for instance lead shot. The sand and shot combination forms an extremely easy compound material to handle and to apply to the tubular member 28 and of course the proportions of sand and shot can be varied to suit any conditions which may be encountered.

It is found that the sand tends to dampen vibrations within a certain range of relatively short wave length whereas the lead shot tends to dampen vibrations of longer wave length. Thus it is seen that in some cases where only relatively short wave length vibrations are encountered, only the sand or similar material is necessary to be used.

On the other hand where longer wave lengths of vibration are encountered, then the combination of the sand and the lead shot is found to be very effective in essentially dampening out both the long and short wave vibrations which may be encountered under different conditions of operation of the doctor.

This forms an inexpensive doctor supporting construction and the sand and the shot also are relatively inexpensive materials by which to dispense with unwanted vibrations in different ranges.

Having thus described my invention and the advantages thereof, I do not wish to be limited to the details herein disclosed, otherwise than as set forth in the claims, but what I claim is:

1. A doctor blade supporting construction comprising an elongated hollow member, a plate extending transversely across said hollow member and at least partially exteriorly thereof in the same plane along one side edge of the hollow member, a doctor blade holder on the exterior edge of the plate and a doctor blade on the holder, means fixedly mounting the holder directly onto the plate, means fixedly mounting the blade on the holder, the blade thereby being in supported, fixed relation to the plate, and means for damping vibrations encountered in the operation of the doctor blade in scraping a surface, said means comprising a flowable discrete relatively heavy material held in the hollow member.

2. The doctor blade supporting construction recited in claim 1 wherein the damping material substantially fills the hollow member.

3. The doctor blade supporting construction recited in claim 1 wherein the damping material consists of sand.

4. The doctor blade supporting construction recited in claim 1 wherein said damping material comprises at least two different discrete materials mixed together, said materials having different densities whereby vibrations of different wave length are damped.

5. The doctor blade supporting construction recited in claim 1 wherein said damping material comprises at least

two different discrete materials of different densities, one being in the nature of lead particles.

6. The doctor blade supporting construction recited in claim 1 wherein said damping material comprises at least two different discrete materials of different densities, one being in the nature of lead particles and the other material comprising lighter weight particles. 5

7. The doctor blade supporting construction recited in claim 1 wherein said damping material comprises at least two different materials of different densities, one being in the nature of lead shot and the other material comprising 10

lighter weight particles, said lighter weight particles being in the nature of sand.
